PIMENTO CORING AND CLEANING
MACHINE

Robert P. Geren and Earl R. Vick, San Diego,
Calif., assignors to Old Mission Packing Cor-
poration, Ltd., San Diego, Calif., a corporation
of Nevada

Application February 4, 1941, Serial No. 377,308

9 Claims. (Cl. 146—52)

Our invention relates to a pimento coring and cleaning machine, more particularly adapted for use in removing cores and seeds from the interior of pimentos or the like at the stem end thereof and the objects of my invention are:

First, to provide a machine of this class which automatically removes the cores from pimentos and washes out the interior of the same after the coring operation thereon;

Second, to provide a machine of this class in which a special high speed pimento coring bit cuts a neat hole in the stem end of the pimento reducing to a minimum the culls created during the coring operation on said pimentos;

Third, to provide a machine of this class in which the pimentos are automatically engaged and held at opposite sides thereof by pimento holding members whereby the pimentos are maintained in steady stationary position during the coring operation thereon;

Fourth, to provide a machine of this class in which a fluid jet member conducts fluid under pressure and directs the same into the interior of the pimento for thoroughly washing seeds and deleterious matter from the interior of the same after they have been cored by said machine;

Fifth, to provide a machine of this class in which pimentos are held in stationary position by a pimento holdown member during the internal washing operation on said pimentos after they have been cored;

Sixth, to provide a machine of this class in which different pimentos are cored and washed at the same time;

Seventh, to provide a machine of this class with novel pimento coring bit means;

Eighth, to provide a novel machine of this class;

Ninth, to provide a machine of this class in which pimento holding members automatically engage pimentos at opposite sides thereof with slight squeezing action thereof whereby said squeezing action stops when said pimento holding members firmly engage said pimentos preventing the same from being crushed when being held by said pimento holding members; and

Tenth, to provide a machine of this class which is very simple and economical of construction, efficient in its action and which will not readily deteriorate or get out of order.

With these and other objects in view as will appear hereinafter, our invention consists of certain novel features of construction, combination and arrangement of parts and portions as will be hereinafter described in detail and particularly

set forth in the appended claims, reference being had to the accompanying drawings and to the characters of reference thereon which form a part of this application in which:

5. Figure 1 is a fragmentary side elevational view of our pimento coring and cleaning machine showing portions thereof broken away and in section and showing by dash lines varying positions of parts thereof; Fig. 2 is an enlarged fragmentary elevational view of the pimento coring bit of our pimento coring and cleaning machine taken from the line 2—2 of Fig. 1; Fig. 3 is a sectional view taken from the line 3—3 of Fig. 2; Fig. 4 is an end elevational view of our pimento

10. coring and cleaning machine showing portions broken away to facilitate the illustration; Fig. 5 is an enlarged sectional view taken from the line 5—5 of Fig. 4; Fig. 6 is an enlarged fragmentary sectional view taken from the line 6—6 of Fig. 4
15. showing parts and portions in elevation to facilitate the illustration; Fig. 7 is a sectional view taken from the line 7—7 of Fig. 4; and Figure 8 is a fragmentary elevational view taken from the line 8—8 of Fig. 4.

20. 25. Similar characters of reference refer to similar parts and portions throughout the several views of the drawings.

The main frame 1, sprocket supporting shafts 2, 3, 4 and 5, sprockets 6, 7, 8 and 9, operating 30. shaft 10, pimento conveyor chain 11, pimento conveyor cups 12, intermittent gear members 13 and 14, cam member 15, cam engaging levers 16 and 17, link member 18, reciprocal shaft 19, motor 20, pimento coring bit 21, pimento holding 35. members 22, levers 23, 24, 25 and 26, shaft 27, rods 28, 29 and 30, detents 31 and 32, pimento holdown member 33, fluid jet member 34, fluid valve 35, brackets 36 and 37, springs 38 and the main operating motor 39 constitute the principal 40. parts and portions of our pimento coring and cleaning machine.

The main frame 1 is substantially rectangular in form, as shown in Fig. 1 of the drawings and is constructed of angle iron or any other suitable 45. material and the various portions of this main frame 1 may be secured together by welding, or otherwise, as desired.

Revolubly mounted in rectangularly disposed 50. relation to each other in connection with this main frame 1 are the sprocket supporting shafts 2, 3, 4 and 5, as shown best in Fig. 1 of the drawings. These sprocket supporting shafts 2, 3, 4 and 5 are supported in the journal members 2a, 3a, 4a and 5a respectively, as shown best in Figs. 55. 1 and 4 of the drawings.

Positioned over the sprockets 6, 7, 8 and 9 is the pimento conveyor chain 11, as shown best in Figs. 1 and 4 of the drawings. The sprockets 6, 7, 8 and 9 are positioned on the shafts 2, 3, 4 and 5 respectively, as shown best in Fig. 1 of the drawings.

The pimento conveyor chain 11 is a substantially conventional link chain and secured thereon are the pimento conveyor cups 12, as shown best in Figs. 1, 4 and 5 of the drawings. Each of the pimento conveyor cups 12 is provided with a base plate portion 12a which is provided with an angularly extending portion 12b. This angularly extending portion 12b is arranged to replace one of the chain link plates, as shown best in Figs. 1 and 5 of the drawings. The base plate portion 12a of each of the pimento conveyor cups 12 is provided with a central opening 12c therein, as shown best in Figs. 4 and 5 of the drawings. This opening 12c is arranged to receive the pimento coring bit 21 as it shifts upwardly into the dash line position, as shown in Figs. 1 and 4 of the drawings. Positioned on this base plate portion 12a around the opening 12c therein are spikes 12d arranged to engage and hold pimentos positioned in the substantially funnel-shaped cup portion 12e which is positioned on the base plate portion 12a outwardly of the spikes 12d and having upwardly and outwardly diverging side wall portions, as shown best in Fig. 5 of the drawings.

The intermittent gear members 13 and 14 are secured on the operating shaft 10 and the sprocket supporting shaft 3 respectively. The operating shaft 10 is driven by the main operating motor 23 in connection with the gear box 39a, as shown best in Fig. 4 of the drawings. The intermittent gear member 13 is arranged to be constantly revolved in connection with the main operating shaft 10. This intermittent gear member 13 is provided with an outwardly extending peg portion 13a arranged to mesh with the slotted stage portions 14a of the intermittent gear member 14. The intermittent gear member 13 is also provided with an arcuate portion 13b arranged to engage the arcuate stage portions 14b of the intermittent gear member 14. This intermittent gear member 14 is preferably of the six stage type and is arranged to revolve the sprocket supporting shaft 3 in connection therewith one-sixth of a revolution with each revolution of the main operating shaft 10, all as shown best in Fig. 7 of the drawings.

Secured on the operating shaft 10 at one side of the intermittent gear member 13 is the cam member 15. This cam member 15 is a substantially circular cam member and is eccentrically mounted in connection with the operating shaft 10, as shown best in Figs. 1 and 4 of the drawings.

Engaging opposite side edges of this cam member 15 are the cam engaging levers 16 and 17, as shown best in Fig. 1 of the drawings. These cam engaging levers 16 and 17 are mounted in connection with the main frame 1 on the pins 16a and 17a respectively. At the opposite side of the cam member 15 from the pins 16a and 17a, the cam engaging levers 16 and 17 are interconnected by means of the link member 18. This link member 18 is pivotally connected with the cam engaging levers 16 and 17 by means of the pins 18a and 18b respectively. The extending end portion 16b of the cam engaging lever 16 is arranged to engage the flange collar member 16c which is rigidly secured on the recipro-

cal shaft 19, as shown best in Fig. 1 of the drawings. This reciprocal shaft 19 is freely reciprocally mounted in the bearings 19a and 19b. Secured on this reciprocal shaft 19 in rigid relation therewith above the flange collar member 16c is a bracket member 20a which is arranged to support the motor 20 in spaced parallel relation with the reciprocal shaft 19, as shown best in Fig. 4 of the drawings.

10 The motor 20 is provided with a revoluble shaft 20b on the upper end of which is rigidly mounted the pimento coring bit 21. This pimento coring bit is hollow and substantially cylindrical in form and is provided with cutaway portions 21a in opposite sides thereof leaving relatively narrow side portions 21b, as shown best in Figs. 2 and 3 of the drawings. The upper end of this pimento coring bit 21 is provided with a substantially hollow cylindrical bit portion 21c on the upper edge of which are positioned saw teeth 21d, as shown best in Fig. 2 of the drawings.

The pimento holding members 22, as shown best in Fig. 4 of the drawings are reciprocally mounted in the substantially U-shaped brackets 37.

25 These pimento holding members 22 are arranged in reciprocally mounted opposed relation to each other, as shown in Fig. 4 of the drawings and are each provided with pimento engaging portions 22a, which portions 22a are substantially arcuate in form, as shown in Fig. 8 of the drawings. Connected with each of these pimento engaging portions 22a are square rod portions 22b; these square rod portions 22b are arranged to extend through opposite sides of each of the brackets 37, as shown best in Fig. 4 of the drawings.

30 Positioned over the outer ends of each of these rod portions 22b is a compression coil spring 38. Each of these springs 38 is arranged to engage the outer side of one of the brackets 37 and a pin 38a in one end of the rod portions 22b, as shown best in Fig. 4 of the drawings. These springs 38 tend to hold the pimento engaging members 22 outwardly toward the brackets 37, as shown best in Fig. 4 of the drawings. These brackets 37 are provided with upwardly extending plate-like portions 37a on which the levers 23 are pivotally mounted by means of the pins 23a, as shown best in Fig. 4 of the drawings.

35 40 The lower ends of the lever 23 are pivotally connected with pimento holding members 22 by means of the pins 23b. Pivotally connected with the levers 23 at the opposite sides of the pins 23a from the pins 23b are the levers 24. These levers 24 are pivotally connected with the levers 23 by means of the pins 24a. At their opposite ends from the pins 24a, the levers 24 are connected together in pivotal relation with each other and are pivotally connected with the rod 39 by means of the pin 39a, as shown best in Figs. 1 and 4 of the drawings. This rod 39 is pivotally connected with the extending end of the lever 26 by means of the pivotally mounted bolt 26a through which said rod 39 extends and in which

45 50 55 it is rigidly secured.

55 60 65 The lever 26 is fixed on the shaft 27, which shaft 27 is revolvably supported by the bracket 36 in connection with the main frame member 1 on the transverse portions thereof, as indicated by dash lines in Fig. 1 of the drawings. At the opposite side of the shaft 27 from the bolt 26a, the rod 28 is pivotally and reciprocally mounted in connection with said lever 26. As shown in Fig. 6 of the drawings, the casing member 31a 70 75 75 of the detents 31 and 32 extends through the

spaced portions of the lever 26 at one end thereof. The rod 28 is positioned intermediate these spaced portions of the lever 26 and is engaged at its opposite sides by the detents 31 and 32 which are substantially spherical in form, all as shown best in Fig. 6 of the drawings. It will be noted that the casing 31a is provided with an opening 31b therein transversely disposed to the axis thereof for receiving the rod 28. The springs 32a and 31b are adjustably supported by the bolts 32b and 31c respectively. It will be understood that by adjusting the bolts 32b and 31c, the compression of the springs 32a and 31b may be varied in relation with the detents 31 and 32 for maintaining the desired frictional engaged relation of the detents 31 and 32 with the rod 28 so that reciprocal movement of the rod 28 upwardly pivots the lever 26 with the shaft 27 forcing the levers 24 downwardly and outwardly pivoting the levers 23 and forcing the pimento holding members 22 inwardly toward each other. When the pimento holding members 22 engage the pimento, the rod 28 slides through the casing 31a in its further reciprocal movement preventing the pimento holding members 22 from being pressed too tightly against the pimento and crushing the same.

Interconnecting the rod 28 and the reciprocal shaft 19 is the rod 28a. This rod 28a is rigidly secured to the upper end of the reciprocal shaft 19 and is arranged in pivotal connection with the rod 28 at its upper end by means of the pin 28b, all as shown best in Fig. 4 of the drawings. Secured on the shaft 27 in spaced relation from the bracket 36 is the lever 25. This lever 25 extends in both directions from the shaft 27 and is provided with a counterweight 25a on its one end and is arranged in pivotal connected relation with the rod 29 at its other end. The rod 29 is secured to a bolt 25b which is pivotally mounted in connection with the lever 25, as shown best in Figs. 1 and 4 of the drawings. This rod 29 is reciprocally mounted in a bracket 29a which is connected with the bracket 36 and extends therefrom, as shown best in Figs. 1 and 4 of the drawings.

Secured on the lower end of this rod 29 is a substantially conical pimento holdown member, as shown in Figs. 1 and 4 of the drawings. This pimento holdown member 33 is substantially hollow and constructed of relatively thin material. The fluid valve 35 is secured to the main frame 1, as shown best in Fig. 1 of the drawings, and is provided with an inlet conductor 35a, as shown best in Figs. 1 and 4 of the drawings. It is also provided with a valve operating lever 35b which is arranged to engage the upper side of the cam engaging lever 16, as shown best in Fig. 1 of the drawings. This lever 35b is pivotally mounted on a pin 35c, all as shown best in Fig. 1 of the drawings. Connected with the outlet end of this fluid valve 35 is the fluid jet member 34, the upper end of which is positioned in spaced relation with the lower side of the pimento conveyor cups 12, as shown best in Figs. 1 and 4 of the drawings. This fluid jet member 34 is positioned in alignment with the pimento holdown member 33, as shown best in Figs. 1 and 4 of the drawings.

The operation of our pimento coring machine is substantially as follows: The operating shaft 10 is constantly operated by the motor 39 and the sprocket supporting shaft 3 is intermittently operated by means of the intermittent gears 13 and 14 providing intermittent shifting action of

the pimento conveyor chain 10 and the pimento conveyor cup 12 positioned thereon. Referring particularly to Fig. 7 of the drawings, it will be observed that the intermittent gear members 13 and 14 are illustrated in operative relation intermediate the stationary stages of the intermittent gear 14. Therefore, the pimento conveyor cups 12 are shown in Fig. 1 of the drawings intermediate their stationary position. Each time the intermittent gear 14 is in stationary position, the pimento conveying cups 12 are in alignment with the pimento coring bit 21 and the pimento holdown member 33 directly above the fluid jet member 34, as shown best in Fig. 1 of the drawings. Each time the intermittent gear 14 stops and positions the pimento conveyor cup 12 in alignment with the pimento coring bit 21 and the pimento holdown member 33, the cam engaging levers 16 and 17 shift the motor 20, together with the pimento coring bit 21 upwardly into the dash line position, as shown in Fig. 1 of the drawings whereby the pimento coring bit 21 extends through an opening 12c in one of the pimento conveying cups 12, as indicated by dash lines in Fig. 1 of the drawings. It will be noted that the motor 20 revolves the pimento coring bit 21 at very high speed so that the saw teeth portions 21b of the pimento coring bit 21 cut a neat opening in the bottom end of the pimento positioned in the pimento conveyor cup 12 in alignment with said pimento coring bit 21.

It will be here noted that as the pimento conveyor cup 12 shifts, together with the pimento conveyor chain 11, the operator of our pimento coring machine positions pimentos in the pimento conveyor cups 12 at the opposite side of the bracket 36 from the pimento holdown member 33, as shown best in Fig. 1 of the drawings. When the intermittent gear member 14 is in stationary position and one of the pimento conveyor cups 12 is in alignment with the pimento coring bit 21, the reciprocal shaft 19 forced upwardly by means of the cam member 15 engaging the cam engaging lever 16 and 17, forces the rod 28 upwardly pivoting the lever 26 and causing the pimento holding members 22 to engage opposite sides of the pimento, as hereinbefore described. Immediately after the pimento holding members 22 engage the pimento, the pimento coring bit 21 enters the stem end of the pimento cutting a neat hole in the end of the pimento and removing the core therefrom together with the bulk of the seeds therein.

It will be noted that the pimento holdown member 33 shifts simultaneously with the operation of the lever 26 so that the pimento holdown member 33 engages a pimento at its upper end after it has been cored by the pimento coring bit 21. While this pimento holdown member 33 is in engagement with the upper end of the pimento, the cam engaging lever 16 forces the lever 35b of the fluid valve 35 upwardly permitting water, or other fluid to pass from the upper end of the jet 34 into the opening cut out by the pimento coring bit 21 and washing the interior of the pimento, cleaning the seeds and other matter out of the pimento. The washing action of one of the pimentos occurs simultaneously with the coring operation of another pimento, each pimento in turn being washed out after it has been cored.

Though we have shown and described a particular construction, combination and arrangement of parts and portions, we do not wish to be limited to this particular construction, combina-

tion and arrangement, but desire to include in the scope of our invention the construction, combination and arrangement substantially as set forth in the appended claims.

Having thus described our invention, what we claim as new and desire to secure by Letters Patent is:

1. In a pimento coring machine of the class described, the combination of an intermittently shiftable pimento conveyor means, a reciprocally mounted revoluble hollow saw-tooth edge pimento coring bit intermittently shiftable to enter pimentos at one end on said conveyor means and pimento holding members arranged to intermittently engage pimentos at the end opposite the end entered by the bit and hold the same in stationary position on said pimento conveyor means during the coring by said bit.

2. In a pimento combined coring and internal cleaning machine of the class described, the combination of an intermittently shiftable pimento conveyor means, a reciprocally mounted revoluble pimento coring bit intermittently shiftable into engagement with pimentos on said conveyor means, pimento holding members arranged to intermittently engage pimentos and hold the same in stationary position on said pimento conveyor means, and fluid jet means arranged to conduct fluid into pimentos on said pimento conveyor means after said pimentos have been cored, to clean the interior of the cored pimento.

3. In a pimento combined coring and internal cleaning machine of the class described, the combination of an intermittently shiftable pimento conveyor means, a reciprocally mounted revoluble pimento coring bit intermittently shiftable into engagement with pimentos on said conveyor means, pimento holding members arranged to intermittently engage pimentos and hold the same in stationary position on said pimento conveyor means, fluid jet means arranged to conduct fluid into pimentos on said pimento conveyor means after said pimentos have been cored to clean the interior of the cored pimento and a holddown member arranged to engage pimentos in opposed relation with said fluid jet means.

4. In a pimento combined coring and internal cleaning machine of the class described, the combination of spaced intermittently shiftable pimento conveyor cups arranged to hold pimentos therein, each of said cups provided with openings therein, a shiftable pimento coring bit arranged to shift through said openings and engage pimentos therein for coring the same, shiftable pimento holding members engageable with opposite sides of said pimentos positioned in said pimento conveyor cup and arranged at opposite sides of the axis of said pimento coring bit, and fluid jet means in the path of said pimento conveyor cups and directed toward said opening whereby fluid passes from said fluid jet into pimentos in said pimento conveyor cup through said opening therein, to clean the interior of the cored pimento.

5. In a pimento combined coring and internal cleaning machine of the class described, the combination of spaced intermittently shiftable pimento conveyor cups arranged to hold pimentos therein, each of said cups provided with openings therein, a shiftable pimento coring bit arranged to shift through said openings and engage pimentos therein for coring the same, shiftable pimento holding members engageable with opposite sides of said pimentos positioned in said pimento conveyor cup and arranged at opposite sides of the

axis of said pimento coring bit, fluid jet means in the path of said pimento conveyor cups and directed toward said opening whereby fluid passes from said fluid jet into pimentos in said pimento conveyor cup through said opening therein to clean the interior of the cored pimento and valve means in communication with said jet means.

6. In a pimento combined coring and internal cleaning machine of the class described, the combination of spaced intermittently shiftable pimento conveyor cups arranged to hold pimentos therein, each of said cups provided with openings therein, a shiftable pimento coring bit arranged to shift through said openings and engage pimentos therein for coring the same, shiftable pimento holding members engageable with opposite sides of said pimentos positioned in said pimento conveyor cup and arranged at opposite sides of the axis of said pimento coring bit, fluid jet means in the path of said pimento conveyor cups and directed toward said opening whereby fluid passes from said fluid jet into pimentos in said pimento conveyor cup through said opening therein to clean the interior of the cored pimento, valve means in communication with said jet means, and cam means arranged to shift said pimento coring bit and intermittently operate said valve means.

7. In a pimento combined coring and internal cleaning machine of the class described, the combination of a shiftable conveyor member provided with conveyor cups thereon, each of said conveyor cups provided with an opening in the lower side thereof, a revolvably mounted coring bit arranged to be shifted through said openings in each of said conveyor cups, and fluid jet means provided with valve means and arranged to conduct fluid upwardly through said openings in each of said conveyor cups to clean the interior of the cored pimento.

8. In a pimento combined coring and internal cleaning machine of the class described, the combination of a shiftable conveyor member provided with conveyor cups thereon, each of said conveyor cups provided with an opening in the lower side thereof, a revolvably mounted coring bit arranged to be shifted through said openings in each of said conveyor cups, fluid jet means provided with valve means and arranged to conduct fluid upwardly through said openings in each of said conveyor cups to clean the interior of the cored pimento, and holddown means above said fluid jet means in opposed relation therewith and arranged to engage pimentos positioned in said conveyor cup above said fluid jet means.

9. In a pimento coring machine of the class described, the combination of intermittently shiftable pimento conveyor cups arranged to hold pimentos therein, each of said cups provided with openings therethrough, a shiftable pimento coring bit arranged to shift through said openings and engage pimentos therein for coring the same, shiftable pimento holding members engageable with opposite sides of said pimentos positioned in said pimento conveyor cup and arranged at opposite sides of the axis of said pimento coring bit, a pivotally mounted lever in operative connection with each of said pimento holding members, and detent means interconnecting said lever and said pimento holding members whereby said pimento holding members are shiftable through said detent means.

ROBERT P. GEREN.
EARL R. VICK.
